UNITED STATES PATENT OFFICE.

FRANK RIEBER, OF SAN FRANCISCO, CALIFORNIA, ASSIGNOR, BY MESNE ASSIGNMENTS, TO RIEBER LABORATORIES, OF SAN FRANCISCO, CALIFORNIA, A CORPORATION OF CALIFORNIA.

APPARATUS FOR EXTRACTING AND INSERTING HIGH-TENSION FUSE-PLUGS.

1,281,069.

Specification of Letters Patent.

Patented Oct. 8, 1918.

Application filed June 27, 1917. Serial No. 177,424.

To all whom it may concern:

Be it known that I, FRANK RIEBER, a citizen of the United States, residing in the city and county of San Francisco and the State of California, have invented certain new and useful Apparatus for Extracting and Inserting High-Tension Fuse-Plugs, of which the following is a specification.

My invention relates to high tension fuse plugs and particularly to means for extracting the plugs from or inserting them in the high tension line.

An object of the invention is to provide an instrument whereby high tension fuse plugs may be safely removed by the lineman, without previously opening the high tension line.

Another object of the invention is to provide such an instrument which is operable by one hand of the lineman to remove or insert the fuse plug.

Another object of the invention is to provide such an instrument which is simple and rugged in construction.

The invention possesses other advantageous features, some of which, with the foregoing, will be set forth at length in the following description where I shall outline in full that form of the invention which I have selected for illustration in the drawings accompanying and forming part of the present specification. In said drawings I have shown one specific form of the instrument of my invention, but it is to be understood that I do not limit myself to such form, because the invention as expressed in the claims, may be embodied in a plurality of forms.

Referring to said drawings:

Figure 1 is an elevation of the instrument. Fig. 2 is a vertical section of the instrument on a larger scale, showing it in engagement with a high tension fuse plug, parts of the device being broken away to reduce the size of the figure.

Fig. 3 is a vertical section of the head of the instrument taken at right angles to Fig. 2.

The instrument comprises a clutch head 2 having a seat or socket therein which opens at one side of the head and which is closed at the other side. The upper portion of the

socket is restricted in width by the overhanging side walls 3 and rear wall 4. The handle 5 of the fuse plug fits in the socket and is held therein against relative movement in a direction longitudinally of the head, by the overhanging walls, under which the enlarged end of the handle 5 engages. The socket is open at the side, so that the head 2 may be readily slipped on or removed transversely from the handle.

Secured to the head 2 is a bar or handle 6 of insulating material, which is held by the lineman in one hand, as he removes or inserts the plug and the handle is of ample length to adequately protect the lineman. In order to prevent the head from becoming disengaged from the fuse plug, by a transverse movement of one with respect to the other, I provide an abutment which is movable into the socket at its open side, thereby closing said side against egress of the plug handle. The abutment is preferably formed as a movable retaining piece 7, which is movable into and out of a seat 8 in the clutch head. The retaining piece is secured to a rod 9 of insulating material lying adjacent and parallel with the handle and this rod 9 is provided on its lower end with a hand grip 12, partly surrounding and slidably engaging the handle. The rod 9 is also suitably guided in a bracket 13 secured to the handle. The retaining piece is preferably beveled on its inner side, or on that side which engages the handle of the plug so that it will operate to wedge the plug handle tightly in the socket.

In operation, the lineman grasps the device, his hand surrounding the exposed section of the handle 6 and also the semi-circular hand grip 12, which is then in its lower position. The clutch head is then moved transversely over the handle of the fuse plug and the lineman then slides his hand upward, moving the retaining piece into the socket, thereby locking the plug in place. The lineman then tightens his grip on the handle, so that there will be no relative movement of the hand grip with respect to the handle and then pulls the fuse plug from its seat. With the use of this instrument, the fuse plug may be withdrawn or inserted

with one hand, permitting the lineman to employ the other hand to sustain himself on the pole.

I claim:

6. 1. In an instrument for withdrawing or inserting high-tension fuse plugs having handles, a head having a socket therein opening on the side of the head and adapted to receive said handle, overhanging shoulders 10 on said head constricting the end opening of said socket, a longitudinally movable retaining device in said head adapted to lock said handle in said socket, an insulating handle on which said head is mounted, and means 15 arranged adjacent said handle for operating said locking device.
2. In an instrument for withdrawing or inserting high-tension fuse plugs having handles, a head having a socket therein opening 20 on the side of the head and adapted to receive said handle, overhanging shoulders on said head constricting the end opening of said socket, a longitudinally movable locking device in said head adapted to lock said 25 handle in said socket, an insulating handle

on which said head is mounted, a hand grip 30 slideable on said handle, and a rod of insulating material connecting said hand grip and locking device.

3. In an instrument for withdrawing or inserting high-tension fuse plugs having handles, a head having a socket therein opening on the side of the head and adapted to receive said handle, a handle of insulating material on which said head is mounted, a 35 retaining device seated in one side of said head and movable into said socket adjacent its opened side, a hand grip slideable on the insulating handle, and a rod of insulating material connecting the retaining device and 40 the hand grip whereby movement of the hand grip along the insulating handle moves the retaining device to release or lock the handle of the fuse plug.

In testimony whereof, I have hereunto set 45 my hand at San Francisco, California, this 13th day of June 1917.

FRANK RIEBER.
